[57] CLAIM

The ornamental design for an image magnifier for computer displays, as shown and described.

DESCRIPTION

FIG. 1 is a front, top and right side perspective view of a printer for electronic computer showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a front, top, and right side perspective view of a second embodiment of our new design;

FIG. 9 is a front elevational view thereof;

FIG. 10 is a top plan view thereof;

FIG. 11 is a left side elevational view thereof;

FIG. 12 is a right side elevational view thereof;

FIG. 13 is a rear elevational view thereof;

FIG. 14 is a bottom plan view thereof;

FIG. 15 is a front, top, and right side perspective view of a third embodiment of our new design;

FIG. 16 is a front elevational view thereof;

FIG. 17 is a top plan view thereof;

FIG. 18 is a left side elevational view thereof;

FIG. 19 is a right side elevational view thereof;

FIG. 20 is a rear elevational view thereof; and

FIG. 21 is a bottom plan view thereof.

FIG. 1

FIG. 2

FIG. 3

FIG. 4

UNITED STATES PATENT AND TRADEMARK OFFICE
CERTIFICATE OF CORRECTION

PATENT NO. : Des. 298,250

Page 1 of 2

DATED : October 25, 1988

INVENTOR(S) : Gary A. Kildall

It is certified that error appears in the above-identified patent and that said Letters Patent is hereby corrected as shown below:

In Column 1, after the section "FOREIGN PATENT DOCUMENTS", delete:

"OTHER PUBLICATIONS"

FIG. 1 is a top, front perspective view of an image magnifier for computer displays showing my new design;
FIG. 2 is a top plan view thereof;
FIG. 3 is a side elevational view thereof, the opposite side being a mirror image;
FIG. 4 is a bottom plan view thereof."

In Column 2 after the subtitled "DESCRIPTION", delete:

FIG. 1 is a front, top and right side perspective view of a printer for electronic computer showing our new design;
FIG. 2 is a front elevational view thereof;
FIG. 3 is a top plan view thereof;
FIG. 4 is a left side elevational view thereof;
FIG. 5 is a right side elevational view thereof;
FIG. 6 is a rear elevational view thereof;
FIG. 7 is a bottom plan view thereof;
FIG. 8 is a front, top and right side perspective view of a second embodiment of our new design;
FIG. 9 is a front elevational view thereof;
FIG. 10 is a top plan view thereof;
FIG. 11 is a left side elevational view thereof;
FIG. 12 is a right side elevational view thereof;
FIG. 13 is a rear elevational view thereof;
FIG. 14 is a bottom plan view thereof;
FIG. 15 is a front, top and right side perspective view of a third embodiment of our new design;
FIG. 16 is a front elevational view thereof;
FIG. 17 is a top plan view thereof;
FIG. 18 is a left side elevational view thereof;
FIG. 19 is a right side elevational view thereof;
